UNITED STATES PATENT OFFICE.

JAMES F. LEMON, OF SYRACUSE, NEW YORK, ASSIGNOR TO THE O. M. EDWARDS COMPANY, INC., OF SYRACUSE, NEW YORK, A CORPORATION OF NEW YORK.

PADLOCK.

1,246,287.

Specification of Letters Patent. Patented Nov. 13, 1917.

Application filed March 10, 1914. Serial No. 823,702.

To all whom it may concern:

Be it known that I, JAMES F. LEMON, a citizen of the United States, and a resident of Syracuse, in the county of Onondaga and State of New York, have invented a certain new and useful Padlock, of which the following is a specification.

This invention has for its object a padlock which is particularly simple in construction, economical in manufacture and highly efficient and durable in use.

In describing this invention, reference is had to the accompanying drawings, in which like characters designate corresponding parts in all the views.

Figure 1 is a front elevation of the padlock, the shackle being shown as swung out of its operative position.

Fig. 2 is an elevation thereof, the front plate or section of the body of the padlock being removed.

Fig. 3 is a view similar to Fig. 2 with the front plate of the locking mechanism removed, and the locking members in their position assumed when locking the shackle.

Fig. 4 is a cross-sectional view on line A—A, Fig. 1.

This padlock comprises, generally, a body, a shackle, and locking mechanism including parts for coacting with both arms of the shackle.

1 designates the body, and 2 the shackle, the body having a central cavity and being composed of front and rear plates or sections, which are substantial duplicates of each other and are shaped to inclose the central cavity or chamber in which the locking mechanism is located, and to form a pair of upwardly extending necks 3 in which the opposing arms 4, 5 of the shackle 2 slide. As illustrated, each of the opposing plates or sections composing the body 1, is formed with a depressed central panel and a circumferential marginal flange extending outwardly from the panel and then inwardly toward the opposite plate or section, said flanges having their edges in contact.

Preferably, the lower ends of the opposing sides of the arms 4, 5, of the shackle are provided with engaging means which are movable into and out of the central cavity

of the body 1, when carried by said ends into and out of engagement with the locking mechanism.

6 is a carrier slideable in the body 1, and to the upper end of which the arm 5 of the shackle 2 is swiveled, the carrier 6 being formed with a lengthwise cavity or passage, and the arm 5 of the shackle having an axial stem 7 at its end, the stem being provided with a head 8 which constitutes a swivel head. The stem and head extend into the passage of the carrier 6 and the carrier is formed with indentations 9 pressed inwardly to contract the passage of the carrier and form shoulders for engaging the upper side of the head 8, thus coupling the carrier to the shackle. The carrier is pressed upwardly by a spring 10 located within the same and bearing against the head 8. The spring is supported, and the carrier guided as will be hereinafter explained.

The locking mechanism includes two sets of locking members interlocking respectively with the engaging means of the opposing arms 4, 5 of the shackle 2 to prevent withdrawal of the hasp from the body, one set being operable by a key, and the other set being operated by the key-operated set. 11, 12 are the sets of locking members, the members of each set being arranged one in advance of the other and the members of one set being paired with those of the other. Said locking members 11, 12 are pivoted at 13, 14 between their ends, and have hooks or engaging heads 15, 16 at their upper ends which are disposed between the arms 4, 5, of the shackle when in its depressed position and take into the corresponding engaging means or notches 17, 18 of the opposing sides of said arms 4, 5. Each locking member 11 is provided with an arm or tail 19 extending below its pivot and having a key-engaging face designed to be engaged by the bit of a key insertible through the keyhole 20. Preferably, the key-engaging face of one locking member 11 is out of alinement with the key-engaging faces of the other locking members, as shown in Fig. 3. The arms or tails 19 constitute the key operated tumblers of the padlock, and, con-

sequently, the members 11 of the padlock are combined locking members and tumblers.

Each member 12 is operated out of operative position by one tumbler or locking member 11 which is provided with an arm 21 extending at a right angle to its arm 11 and hook arm 15, and co-acting with the tail or arm 22 of said member 12 below its pivot 14, the tail 22 having an inclined surface 23 with which the end of the arm 21 coacts to cam the member 12 out of operative position as the tumbler or locking member 11 is moved by the key out of operative position.

Each pair of locking members 11 and 12 is moved into operative position by a spring 24 interposed between said locking members 11 and 12 and acting on their upper ends in opposite directions, this spring also permitting the locking members 11 and 12 to yield independently and being substantially V shape and having the ends of its branches located in notches 25 on opposing sides of the locking members 11 and 12. The upper sides of the notches 17 and 18 and the heads 15, 16 are shaped to cause the locking members 11, 12 to move against the action of the springs 24 when the shackle is being moved downwardly into locking position. There is a spring 24 for each pair of members 11, 12.

The locking mechanism further includes front and rear plates 26, 27 which support the locking parts 11, 12 and the shackle carrier 6, the plates being located contiguous to the front and rear sides of the body 1, and connected together and spaced apart by the pivots 13, 14 and by additional pins or rivets 28 which also extend through the front and rear sides of the body 1 and serve to secure together the plates forming the body. One of the plates, as the rear plate 27, is formed with a vertical marginal flange or lug 29 bent at a right angle thereto for engaging one of the sides of the carrier 6, and the front plate 26 is formed with a lug 30 bent at an oblique angle thereto and engaging an obliquely arranged side 31 on the carrier 6, the flange 29 and lug 30 forming a guide for the carrier. The carrier is also guided by the neck 3 and by guiding faces provided on the locking members 12 and opposed to, and spaced apart from, the flange 29 and the lug 30. The lug 30 also acts as a stop for limiting the throw of the carrier 6, the stop engaging the surfaces 32 at opposite ends of said inclined face 31 of the carrier.

One of the plates, as the rear plate 27, is also provided with a lug 33 bent at a right angle thereto and facing upwardly and arranged to form an abutment for the carrier 6 and a seat for the spring 10, the lug 33 having an upwardly extending projection or pin 34 normally extending into the carrier 6 and preventing the spring 10 from displacement. The lower end of the spring en-

circles said pin 34 and abuts against the lug 33.

In operation, when the key is inserted in the keyhole, the bit thereof engages the arms 19 of the tumblers 11 and moves said tumblers to carry their heads 15 out of interlocking engagement with the arm 4 of the shackle and at the same time, the arms 21 of the tumblers 11 operate the locking members 12 to withdraw their heads 16 out of engagement with the arm 5 of the shackle, whereupon the spring 10 shifts the carrier 6 and the shackle upwardly until the swivel joint is located outside of the body, after which the shackle can be opened or swung in any direction and in a complete circle if desired. To lock the device, the shackle is thrown into the position shown in Fig. 2, pressed inwardly and the arms 4, 5 thereof engage with the heads 15, 16 of the locking members. The necks 3 are non-circular and the arms 4, 5 of the shackle slidably fit the same so that the shackle cannot swivel until the upper end of the carrier moves above the neck 3 in which it slides.

This lock is particularly advantageous in that the shackle is locked at both ends thereof, and further in that the locking mechanism consists of a small number of compactly-arranged and easily-made parts.

What I claim is:

1. A padlock comprising a body, a sliding shackle, and locking mechanism within the body including a member coacting with one of the arms of the shackle, and means having interlocking engagement with the other arm of the shackle, said means being positively disengaged from the last-named arm of the shackle by said member, substantially as and for the purpose described.

2. A padlock comprising a body, a sliding shackle having opposing arms, and locking mechanism within the body including a member interlocking with one of the arms of the shackle, a member interlocking with the other arm of the shackle, the second member being movable out of interlocking position by the first-mentioned member, and a spring interposed between said members for forcing them into interlocking position, and permitting them to yield independently of each other, substantially as and for the purpose specified.

3. A padlock comprising a body, a sliding shackle having opposing arms, and locking mechanism within the body including a plurality of members arranged one in advance of the other, and each interlocking with one of the arms of the shackle and having a key-engaging face disposed in the path of the key, the key-engaging face of one member being out of alignment with the key-engaging face of another member, a plurality of additional members arranged one in advance of the other and each being compli-

mental to, and movable out of interlocking position by, one of the first-mentioned members, and springs interposed between said members, each spring coacting with one of 5 the first-mentioned members and with the complementary second-named member, substantially as and for the purpose set forth.

4. A padlock comprising a body formed with a pair of non-circular necks, a shackle 10 having non-circular arms slidably fitting the necks when the shackle is in locked position, one arm of the shackle having a circular spindle movable into the corresponding neck when the shackle is moved outwardly and the non-circular portions thereof are above the necks, substantially as and for the purpose specified.

5. A padlock comprising a body, a movable shackle, and locking mechanism including 20 movable members coacting with opposite arms of the shackle and having engaging heads at corresponding ends for engaging said arms, the members being movable reversely relatively to each other, and one 25 member having a key-engaging part and means for shifting the other member out of shackle-engaging position, and a spring interposed between the members and tending to move the same into shackle-engaging position, substantially as and for the purpose described.

6. A padlock comprising a body, a movable shackle, and locking mechanism comprising pivoted members extending between the 35 arms of the shackle and having parts for interlocking with the same, one member having an arm projecting toward the other member and coacting therewith to operate the same, and one of the members having an 40 arm arranged to be operated by the bit of the key, substantially as and for the purpose specified.

7. A padlock comprising a body, a shackle, a carrier for the shackle slidable in 45 the body, one arm of the shackle being swiveled to the carrier, and locking means movable within the body and coacting with the shackle, substantially as and for the purpose described.

50 8. A padlock comprising a body, a shackle and a sliding carrier located in the body, the shackle having a swivel head at one end thereof connected to the carrier and the carrier being formed with an indentation overlying the head to hold the head and the shackle from removal, substantially as and for the purpose described.

9. A padlock comprising a body, a shackle, a carrier for the shackle slidable in 60 the body and formed with an internal cavity, one arm of the shackle being swiveled to the carrier, locking means movable within the body and coacting with the shackle, and a spring within the cavity of the carrier and 65 acting on said carrier to move the same and

force the shackle outwardly relatively to the body, substantially as and for the purpose set forth.

10. A padlock comprising a body, a shackle, a sliding carrier located in the body, 70 and formed with a lengthwise passage, the shackle having a swivel head at one end thereof extending into the passage of the carrier and the carrier being formed with an indentation projecting over the head to hold the head from removal, and a spring located in the carrier and pressing upwardly on the head, substantially as and for the purpose set forth.

11. A padlock comprising a body having 80 a central cavity, a sliding shackle and a locking mechanism within the cavity comprising opposing plates lying contiguous to the front and rear sides of the body and movable members carried between the plates, substantially as and for the purpose described.

12. A padlock comprising a body, a shackle, a carrier for the shackle slidable in the body, one arm of the shackle being swiveled to the carrier, a plate located within the body and having guiding means for the carrier, locking means movable within the body and coacting with the shackle, and a spring acting on the carrier to move the same and force the shackle outwardly relatively to the body, substantially as and for the purpose described.

13. A padlock comprising a body, a shackle, a carrier for the shackle slidable in the body, one arm of the shackle being swiveled to the carrier, a plate located within the body and having a lug, locking means movable within the body and coacting with the shackle, and a spring coacting with said lug and acting on the carrier to move the 105 same and force the shackle outwardly relatively to the body, substantially as and for the purpose specified.

14. A padlock comprising a body, a shackle, a shackle carrier slidable in the 110 body, the shackle being swiveled to one end of the carrier, and the carrier being formed with a lengthwise passage, a plate located within the body and having a lug extending under the lower end of the carrier, and a spring pressing the carrier upwardly, the spring being located in said passage and bearing at its lower end against said lug, substantially as and for the purpose specified.

15. A padlock comprising a hollow body, a shackle, a carrier for the shackle slidable in the body, the shackle being swiveled to the carrier, opposing plates arranged within the body between opposite sides thereof and having their opposing surfaces provided with means for guiding the carrier, and locking means movable within the body and coacting with the shackle, substantially as and for the purpose set forth.

16. A padlock comprising a hollow body, opposing plates carried between opposite sides of the body and provided with guiding means, a shackle, locking means movable between the plates and coacting with the shackle, said means having a guiding face spaced apart from the guiding means of the opposing plates, and a carrier for the shackle 40

slidable in the body, the shackle being swiveled to the carrier, and said carrier slidably engaging the guiding means of the opposing plates and the guiding face of the locking means, substantially as and for the purpose described.
17. A padlock comprising a body, a shackle, a shackle carrier slidably in the body, the shackle being swiveled to the carrier, and locking mechanism including opposing plates, and a movable locking member carried between the plates and coacting with the shackle, the plates having angularly arranged lugs forming a guide for the carrier, and the carrier being formed with a stop surface for engaging one of the lugs to limit the throw of the carrier, substantially as and for the purpose set forth. 50
55
18. A padlock comprising a body, a shackle, a shackle carrier slidably in the body, the shackle being swiveled to the carrier, and locking mechanism including opposing plates, and a movable locking member carried between the plates and coacting with the shackle, the plates having angularly arranged lugs forming a guide for the carrier, and the carrier being formed with a stop surface for engaging one of the lugs to limit the throw of the carrier, substantially as and for the purpose set forth. 60
65

to limit the throw of the carrier, one of the plates being also formed with a lug arranged under the lower end of the carrier, substantially as and for the purpose described. 40

19. A padlock comprising a body, a shackle, a shackle carrier slidably in the body, the shackle being swiveled to the carrier, and the shackle carrier being formed with a passage opening through its lower end, locking mechanism including opposing plates, and a movable locking member carried between the plates and coacting with the shackle, the plates having angularly arranged lugs forming a guide for the carrier, and the carrier being formed with a stop surface for engaging one of the lugs to limit the movement of the carrier, one of the plates being also formed with a lug arranged under the lower end of the carrier, the last mentioned lug having a projection extending into the carrier, and a spring located within the carrier and encircling the projection and resting on the last mentioned lug, substantially as and for the purpose specified. 50

60

In testimony whereof, I have hereunto signed my name in the presence of two attesting witnesses, at Syracuse, in the county 65
of Onondaga, in the State of New York, this 25th day of February, 1914.

JAMES F. LEMON.
